EDGAR C. CHANDLER, OF PHILADELPHIA, PENNSYLVANIA.

PATTERN MECHANISM FOR KNITTING-MACHINES.

953,122.

Specification of Letters Patent. Patented Mar. 29, 1910.

Application filed August 18, 1908. Serial No. 449,181.

To all whom it may concern:

Be it known that I, EDGAR C. CHANDLER, citizen of the United States, residing at Philadelphia, in the county of Philadelphia and State of Pennsylvania, have invented certain new and useful Improvements in Pattern Mechanism for Knitting-Machines, of which the following is a specification.

The object of this invention is to provide in a knitting machine a simple and efficient construction and organization of parts whereby various different patterning effects may be produced in the product of the machine by moving different threads into and out of operative relation to the needles, to be knitted thereby, at predetermined intervals; by causing at predetermined intervals certain of the needles to produce "tuck" stitches while the remaining needles produce the regular stitches; and by causing the needles to cease the production of the "tuck" stitches at predetermined intervals.

The invention consists in the novel construction and combinations of parts which will be hereinafter fully described and claimed.

In the drawings:—Figure 1 is a plan view of a knitting machine embodying my invention. Fig. 2 is a side elevation thereof. Fig. 3 is a longitudinal section, as on the line *a—a* of Fig. 1. Figs. 4 and 10 are sections as on the lines *b—b* and *k—k* of Fig. 1, respectively. Fig. 5 is a section as on the line *c—c* of Fig. 1. Fig. 6 is a view of the pawl raising arm, detached. Fig. 7 is a section as on the line *d—d* of Fig. 1. Fig. 8 is a section as on the line *e—e* of Fig. 1. Fig. 9 is a section as on the line *f—f* of Fig. 1. Fig. 11 is a plan view of a portion of the thread changing mechanism, enlarged. Fig. 12 is a section as on the line *g—g* of Fig. 11. Fig. 13 is a section as on the line *h—h* of Fig. 11. Fig. 14 is a development of a portion of the interior of the cam cylinder showing one of the two sets of knitting cams and one of the adjustable needle-raising cams. Fig. 15 is a horizontal section as on the line *i—i* of Fig. 2.

The main frame of the machine comprises a bed plate 1, and a suitable supporting standard 2 therefor. Mounted in suitable bearings in the standard 2 is the main driving shaft 3, the outer end of which is provided with the usual fast and loose pulleys 4 and 5, by means of which power may be

applied to the shaft. The inner end of the shaft 3 is provided with a beveled gear wheel 6 which engages the teeth of a similar gear wheel 7 formed on the cam cylinder 8 which is rotatably mounted in the bed plate 1. Within the cam cylinder 8 is the needle cylinder 9, provided with the usual vertical grooves into which are fitted the needles 10 of usual construction. The cam cylinder 9 carries the usual cams for vertically reciprocating the needles for the production of the stitches in the common and well known manner. In the present invention two sets of knitting cams of usual construction are carried by the cam cylinder and on opposite sides thereof, as at A and B, whereby, during the rotation of the cam cylinder 8 the needles will be actuated to produce two rows of stitches for every revolution of the cam cylinder. Each set of knitting cams A and B is like the construction shown in Fig. 12.

The construction and operation of the knitting cams for the production of the stitches are common and well known and no detailed description or illustration thereof is deemed necessary herein.

In carrying out my invention, I employ an automatically controlled mechanism to raise certain of the needles so that their latches will escape their engaged loops of thread while the latches of other needles are permitted to remain in their engaged loops of thread to produce "tuck" stitches during the knitting operation, to control the pattern effect of the fabric being knitted; and I also employ an automatically operated thread-changing mechanism for the knitting cams A, by means of which either of two threads of different colors may be fed to the needles to control the pattern effect of the fabric being knitted.

Thread-changing mechanism:— Rising from the cam cylinder 8 on opposite sides thereof, are posts 18 and 19, between which extends a frame 20 in which is formed a ring 21 which surrounds the needles 10 and forms the usual guard for the latches thereof. This ring 21 is provided with a thread-guiding eye 22 through which a thread is directed to the needles adjacent the knitting cams B. One side of the frame 20 extends upwardly adjacent the knitting cams A and is provided with two thread-guiding parts or levers 23 and 24, which are arranged side by side within an opening in the frame 20,

the levers 23 and 24 being separated by a thin plate 25. The upper portions of the levers 23 and 24 are pivotally mounted on a pin 26 on the frame 20, and the lower ends of the levers 23 and 24 are provided with thread-guiding eyes 27 and 28 respectively, each of which is adapted to be moved to an active position outwardly of the circular series of needles to direct its thread thereto adjacent the knitting cams A, and each of which is adapted to be moved to an inactive position inwardly of the circular series of needles to prevent its thread being engaged thereby during the knitting operation. The thread-guiding eyes 27 and 28 are adapted to receive threads of different colors, and the levers 23 and 24 are adapted to be operated to move the eyes 27 and 28 to the active and inactive positions in alternate succession, to change the color of the thread being delivered to the knitting cams A, as will hereinafter appear. The upper ends of the levers 23 and 24 are connected by springs 29 and 30 respectively to the frame 20. The springs 29 and 30 extend through an opening in a disk 32 hereinafter described, the tendency of the springs being to draw down the upper ends of the levers and move the thread-guiding eyes in the lower ends thereof to the inoperative position, inwardly of the circular series of needles. The lower faces of the upper ends of the levers 23 and 24 are adapted to be engaged by a cam 31 projecting from the disk 32 which is rotatably mounted on a screw 33 on the frame 20.

Fitted to guideways in the frame 20, directly beneath the disk 32, are two reciprocal bars 34 and 35, the outer ends of which converge toward and overlap each other as shown, the outer end of the bar 35 being located above the outer end of the bar 34. The bar 34 is arranged on one side of the screw 33 and the bar 35 is arranged on the other side thereof. The bar 34 is connected to the disk 32 by a pin 36 extending through a slot 37 in the disk, and the bar 35 is connected to the disk 32 by a pin 38 extending through a slot 39 in the disk. The bars 34 and 35 are adapted to be moved in and out through their guideways so as to project the outer ends thereof beyond the frame 20, and when one bar is moved outwardly to project its end outwardly of the frame 20, the other bar is moved inwardly by the operation of the disk.

When the parts are in the position shown, the outer end of the bar 34 is projected beyond the frame 20, and the upper end of the lever 24 is held in the raised position by the top of the cam 31 against the action of its spring 30, thus holding the thread-guiding eye 28 in the active position outwardly of the circular series of needles, and the upper end of the lever 23 is drawn downwardly

by the action of its spring 29 which holds the thread-guiding eye 27 in the inactive position inwardly of the circular series of needles. In this position of the levers 23 and 24, the thread-guiding eye 28 in the active position is delivering thread to the needles to be acted upon thereby. When, however, it is desired to discontinue the knitting of the thread fed by the eye 28 and to knit the thread fed by the eye 27, the lever 23 is first moved to a position outwardly of the needles adjacent the position of the lever 24, to bring the thread-guiding eye 27 to the active position, and the lever 24 is then moved to a position inwardly of the needles adjacent the position previously occupied by the lever 23, to bring the thread-guiding eye 28 to the inactive position. This is accomplished by moving the bar 34 inwardly which causes the pin 36 to engage the wall of the slot 37 and rotate the disk 32 a partial revolution, causing the wall of the slot 39 to engage the pin 38 and move the bar 35 outwardly to project its outer end beyond the frame 20 in a position above the position previously occupied by the outer end of the bar 34. During the initial movement of the disk 32 by the bar 34, the upper end of the lever 23 is acted upon by the inclined end of the cam 31, and raised to a position adjacent the raised end of the lever 24, bringing the thread-guiding eye 27 to the active position outwardly of the needles; and as the disk 32 completes its movement by the bar 34, the upper end of the lever 24, under the influence of its spring 30, rides down the other inclined end of the cam 31 and moves the thread-guiding eye 28 to the inactive position inwardly of the needles, while the upper end of the lever 23 remains upon the top of the cam 31 to retain the thread-guiding eye 27 in the active position. When it is desired to again change the thread being delivered to the needles through the eyes 27 and 28, the bar 35 is moved inward; which, through its pin-and-slot connection with the disk 32, returns the disk 32, its cam 31, and the bar 34, to the position shown, thus raising the upper end of the lever 24 and lowering the upper end of the lever 23, and bringing the thread-guiding eye 28 back into active position and moving the thread-guiding eye 27 to the inactive position.

It will be clear, from this description, that when a change of thread delivered to the knitting cams A is desired, it may be effected by moving inwardly the outer end of the bar 34 or 35 which is projecting beyond the frame 20. The bars 34 and 35 are adapted to be moved inwardly in alternate succession and at predetermined intervals, to effect the changing of the thread, by the action of a horizontally arranged cam plate 40, movable vertically into the path traversed by the

outer end of either the bar 34 or the bar 35 during the rotation of the cam cylinder when either of said bars is in the outer position. The inner edge of the cam plate 40 is provided with a central portion 41, concentric with the cam cylinder, an end portion 42 beveled outwardly from the central portion 41, and an end portion 43 beveled inwardly from the central portion. When either of the bars 34 and 35 acts upon the cam plate 40 during the rotation of the cam cylinder, the beveled portion 42 first actuates the bar sufficiently to cause the cam 31 to move the inactive thread-guiding lever to the active position, without moving the active thread-guiding lever to the inactive position. Therefore, during the movement of the bar over the central portion 42 of the cam plate 40, the thread-guiding eyes of both levers 23 and 24 are in the active position. When the bar engages the beveled portion 43 of the cam, it completes its inward movement, and at the same time completes the movement of the cam 31 to permit the spring of the previously active lever to move its thread-guiding eye into the inactive position. The cam plate 40 is mounted on the upper end of a vertically movable rod 45, which is fitted to perforated projections on a bracket 44 rising from the bed plate 1. The cam plate 40 and the rod 45 are prevented from turning about the axis of the rod 45 by a pin 46 projecting downwardly from the plate 40 parallel to the rod 45, and slidingly fitted to an opening in the bracket 44. The rod 45 is provided with a lateral projection 47 between which and the top of the bracket is interposed a spring 48, which encircles the rod 45 and bears against the upper portion of the bracket 44 and the lateral projection 47 in a manner to depress the rod 45.

Extending vertically through the projection 47 is an adjustable screw 49 the lower end of which rests upon the free end of an arm 50 projecting fixedly from a shaft 51 which is mounted in bearings in a bracket 52 projecting from the bed plate 1. This shaft 51 has fixed thereto one end of an arm 53, which extends from the shaft substantially parallel to the arm 50. By automatic mechanism hereinafter explained, the arms 50 and 53 are raised and lowered, thus raising and lowering the rod 45 and therefore the cam plate 40 into and out of each of the paths traversed by the outer ends of the bars 34 and 35, to control the thread-changing mechanism for the production of different pattern effects in the fabric being knitted.

Stitch tucking mechanism:—Directly in rear of the knitting cams B is a needle-operating wheel 54 which inclines upwardly in a direction away from the knitting cams; and directly in rear of the knitting cams A is

a needle-operating wheel 55 which inclines upwardly in a direction away from the knitting cams. The wheels 54 and 55 are mounted to rotate on pivot studs 56 and 57 respectively, carried by the cam cylinder 8. 70 The edge of each wheel is provided with suitable notches adapted to engage the butts of certain predetermined needles and raise them so that their latches will escape their engaged loops of thread after they have 75 been acted upon by the preceding knitting cams, and each wheel is also provided with slots between the notches for the passage therethrough of the butts of the needles not raised by the wheel. The latches of the 80 needles not raised by the wheels 54 and 55 are thus permitted to remain in their engaged loops of thread, thus causing certain needles to "tuck" during the knitting operation and produce pattern effects upon the 85 fabric being knitted.

Directly in rear of each wheel 54 and 55 is a pattern controlling, needle-operating cam 58, which is formed on the inner end of a radially extending bar 59. The bar 59 90 is pivotally mounted, as at 60, on a bracket 61 projecting from and carried by the cam cylinder 8. The bars 59 are adapted to be rocked on their pivots by mechanism hereinafter described, to raise and lower the 95 cams 58, and the cams 58 are held in either their raised or lowered position by the action of a flat spring 62 secured to the brackets 61 and engaging V-shaped lateral faces of the cams 58. When the cams 58 are in the lowered position, the butts of the needles are unaffected thereby. When, however, the cams 58 are in the raised position, they act upon the butts of all the needles including those not acted upon by the notches of the preceding wheels 54 and 55 and raise said needles so that their latches also escape their 100 engaged loops of thread. Thus it will be seen that when the cams 58 are in the raised position, all of the needles, after they have 110 been acted upon by the knitting cams A and B will be raised so that their latches will escape their engaged loops of thread, and that therefore no tucking will take place; and that when the cams 58 are in the lowered 115 position, the needle butts will be unaffected thereby and certain needles controlled by the wheels 54 and 55 will be caused to tuck as previously explained. Thus the raising and lowering of the cams will control the tucking 120 operation; or, in other words, when the cams 58 are in the raised position, no tucking will take place, and when the cams are in the lowered position the tucking operation will take place.

The notches of the wheels 54 and 55 may be arranged to engage any predetermined needles to control the pattern effect of the tucking stitches in the product of the machine, and either one or both of the wheels 130

4
54 and 55 may be removed from the machine and other wheels having differently arranged notches to engage different needles may be substituted therefor. Thus a great 5 variety of pattern effects, due to the tucked stitches, may be produced in the knitted fabric by the employment of different wheels having differently arranged needle-engaging notches.

10 The outer ends of the cam bars 59 are adapted to be engaged by two reciprocative pins 62 and 63, arranged one above the other. These pins are adapted to be projected in alternate succession into the path traversed 15 by the outer ends of the cam bars, and the outer ends of the cam bars are provided with upper and lower beveled surfaces which are adapted to be engaged by the pins 62 and 63 to raise and lower the outer ends of 20 the bars 59, and at the same time raise and lower the cams 58 carried by the inner ends thereof. The pin 62 is so positioned with relation to the path of travel of the outer ends of the bars 59, that when it is projected 25 into the path thereof it will act upon the upper beveled faces of the outer ends of the bars to depress them and raise the cams 58. And the pin 63 is so positioned with relation to the path of travel of the outer 30 ends of the bars 59 that when it is projected into the path thereof it will act upon the lower beveled faces of the outer ends of the bars to raise them and lower the cams 58. The pins 62 and 63 are fitted to horizontal 35 openings in the bracket 44 and their outer ends are pivotally connected to the upper and lower ends of a plate or lever 64 which is pivotally connected to the bracket 44 as at 65, centrally between the two pins 62 and 40 63. The central portion of the plate or lever 64 extends outwardly from the bracket 44 and is connected by an upwardly extending link 66 to a horizontally arranged arm 67 which is pivotally mounted on the shaft 51 45 hereinbefore mentioned. The free end of the arm 67 is drawn downward by the action of a spring 68, one end of which is connected to the arm 67 and the other end of which is connected to the bracket 44. From 50 this construction it will be seen that when the arm 67 is raised against the action of the spring 68 the link 66 will act upon and rock the plate or lever 64 in a manner to withdraw the pin 63 from the path of the 55 cam bars 59, and project the pin 62 into the path of the cam bars 59; and when the arm 67 is lowered by the action of the spring 68, the link will act upon and rock the plate or lever 64 in a manner to withdraw the 60 pin 67 from the path of the cam bars 59 and project the pin 63 into the path of the cam bars; so that when the pin 63 is projected inwardly the cams 58 will be lowered, 65 permitting the production of the tucked stitches; and when the pin 62 is projected

inwardly the cams 58 will be raised to cause the needles to cease the production of the tucked stitches.

By automatic mechanism hereinafter explained, the arm 67 is raised and lowered, 70 to thus control the production or non-production of the tucked stitches.

Automatic mechanism for controlling the thread-changing mechanism and the stitch-tucking mechanism.—Directly beneath the 75 arms 50 and 53 of the thread-changing mechanism and the arm 67 of the stitch-tucking mechanism, are two independently rotatable members which, in the present embodiment of my invention, are two drums 80 69 and 70. The drum 70 is fixed to a shaft 71 which is mounted in bearings projecting from the bed plate 1, and the drum 69 surrounds and is rotatably mounted upon the drum 70. The drum 69 is only about one 85 half the length of the drum 70; so that a portion of the periphery of the drum 70 will be exposed while the entire periphery of the drum 69 is exposed. The arms 50 and 53 are provided with downward projections 72 and 73 respectively, which are adapted to move into and out of the paths traversed by projecting blocks 74 and 75 carried by the drums 69 and 70 respectively; and the arm 67 is provided with two downward projections 76 and 77, which are adapted to move into and out of the paths traversed by projecting blocks 78 and 79 carried by the drums 69 and 70 respectively. Thus it will be seen that when the drums 90 69 and 70 are rotated independently of each other, the thread-changing mechanism will be controlled by the arms 50 and 53 being raised and lowered by the operation of the blocks 74 and 75; and that the stitch-tucking 95 mechanism will be controlled by the arm 67 being raised and lowered by the operation of the blocks 78 and 79. The drums 69 and 70 are provided with screw-threaded holes 100 for the reception of screws to secure other blocks to the drums in the path of the blocks 74, 75, 78, and 79, or for changing the location of these blocks with respect to each other and the drums 69 and 70, so that they 105 will act upon the arms 50 and 53 and the arm 67 at different times with relation to the movement of the drums.

By employing two independently rotatable members or drums and by independently controlling both the thread-changing 110 mechanism and the stitch-tucking mechanism by each of said drums, I am enabled to obtain a much wider range of variation in the pattern of the fabric being knitted than if a single drum were employed. 115

I shall now describe the mechanism for actuating the drums independently of each other at certain intervals during the operation of the machine.

Formed on or secured to one end of the 130

inner drum 70 is a ratchet wheel 80, and formed on or secured to one end of the outer drum adjacent the ratchet wheel 80 is a ratchet wheel 81. The teeth of the ratchet wheel 80 are directed opposite to the teeth of the ratchet wheel 81 so that they and the drums may be rotated in opposite directions. Engaged with the ratchet wheels 80 and 81 are pawls 82 and 83 respectively, the pawls 82 and 83 being carried by the upper end of a lever 84 fulcrumed on the shaft 71. The lower end of the lever 84 is connected by an arm 85 to a wheel 86 away from the center thereof, whereby, during the rotation of the wheel 86, the lever 84 will be rocked back and forth. The wheel 86 is carried by a shaft 87 having its bearings in the main frame, and the shaft 87 is actuated from the main shaft 3 by the interposed gear wheel 88 and pinion 89. Thus, during the operation of the machine, the lever 84 will be rocked back and forth. The movement of the upper end of the lever 84 in one direction will cause the pawl 83 to engage a tooth 69 of the ratchet wheel 81 and advance the drum 70 the distance of one tooth; and the movement of the upper end of the lever 84 in the reverse direction will cause the pawl 82 to engage a tooth of the ratchet wheel 80 and advance the drum 70 the distance of one tooth in an opposite direction to the movement of the drum 69.

In order to disengage the pawl 82 from the ratchet wheel 80 so that it will discontinue to advance the drum 70 at certain predetermined intervals, for a purpose herein-after explained, I provide an arm 90, one end of which is pivotally mounted on a bracket 91 on the bed plate 1, and the other end of which extends to a position directly beneath the path of movement of the pawl 82, so that when the arm 90 is raised, the nose of the pawl 82 will ride over the arm and be prevented from engaging the teeth of the ratchet wheel 80, and when the arm 90 is lowered the pawl 82 will be permitted to drop into engagement with said teeth. The arm 90 is raised at certain intervals by pins 92 which project from a circular series 50 of screw-threaded holes 93 in the face of the ratchet wheel 80 into which the pins 92 are screwed. The timing of the disengagement of the pawl 82 from the ratchet wheel 80 with relation to its movement may be controlled 55 and regulated by employing a greater or less number of pins 92 and by changing their positions about the circular series of openings 93. After the arm 90 has been raised by one of the pins 92, it is held in the raised position by a latch arm 94 provided with a shoulder 95 adapted to engage a lateral projection 96 on the arm 90. The lower end of the latch arm 94 is fixed to a rock shaft 97 which is mounted in bearings in brackets depending from the bed plate, 1. The upper

end of the arm 94 is drawn normally toward the projection 96 by a spring 98, one end of which is connected to the arm 94 and the other end of which is connected to a projection 99 rising from the arm 90 adjacent the pivot thereof. This spring 98 also tends to move the free end of the arm 90 downwardly from engagement with the pawl, 82. As the arm 90 is being raised by a pin 92, the arm does not raise the pawl 82 from the tooth of the wheel 80 with which it is then engaged, but it is raised into position to prevent the pawl dropping into engagement with the next succeeding tooth. This being done, the spring 98 draws the latch arm 94 into engagement with the projection 96 on the arm 90 to maintain the arm elevated while the pin 92, which raised the arm 90, moves from engagement therewith before the wheel 80 comes to rest, so that the arm 90 may drop from the pawl 82 when the arm 90 is released by the latch arm 94.

When the shoulder 95 is in engagement with the projection 96, and the pawl 82 is out of engagement with the ratchet wheel 80, and it is desired to permit the pawl 82 to drop into engagement with the ratchet wheel 80, the shaft 97 is rocked to disengage the latch arm 94 from the projection 96, thus permitting the arm 90 and pawl 82 to drop. The latch arm 94 is thus operated at certain predetermined intervals by the following mechanism:—One end of the shaft 97 extends outwardly and is provided with an arm 100 the free end of which is provided with a dog 101 arranged directly over a pattern chain 102 which passes over a sprocket wheel 103 on a shaft 104 which is mounted to rotate in a suitable bearing. The lower end of the chain 102 passes around a weighted, grooved wheel 105, which is supported by the chain. The links of the chain, at certain intervals, are provided with projections 106 which, as they pass the free end of the arm 100 during the rotation of the sprocket wheel 103, are adapted to engage the dog 101 and raise the arm 100 in a manner to rock the shaft 97 and disengage the latch arm 94 from the pawl-engaging arm 90 and return the pawl 82 into engagement with the sprocket wheel 80. The shaft 104, and therewith the sprocket wheel 103, is continuously and slowly rotated by a wheel 107 on the shaft 104, the periphery of the wheel 107 being provided with small comb-like projections which are engaged by the fabric (shown by dot-and-dash lines) which, as it passes from the needles to and between a pair of take-up rollers 108, engages the projections and rotates the wheel 107. The take-up rollers 108 are journaled in a frame 109 one end of which is pivotally mounted on a shaft 110 carried by brackets depending from the bed plate. The shaft of one take-up roller 108 is provided with a gear 130

wheel 111 which is engaged by a pinion 112 on one end of a shaft 113 journaled in the frame 109. The other end of the shaft 113 is provided with a grooved pulley 114 around which passes a belt 115 which also passes around a grooved pulley 116 on the main driving shaft 3.

During the knitting operation, the fabric is drawn from the needles by the weight of 10 the free end of the frame 109, which is supported by the fabric engaging the take-up rollers 108. As the frame 109 moves downwardly in drawing the fabric from the needles, the frictional engagement of the 15 belt 115 with the wheel 114 increases until it is sufficient to turn the shaft 113 and therewith the take-up rollers 108 in a manner to feed the fabric downwardly between said rollers, thus raising the free end of the 20 frame 109 and decreasing the frictional engagement of the belt 115 with the pulley 114 until it is insufficient to rotate the take-up rollers; whereupon the free end of the frame 109 again moves downwardly until the frictional engagement of the belt 115 with the 25 pulley 114 is again sufficient to cause the actuation of the take-up rollers 108. Thus the free end of the frame 109 is slightly raised and lowered during the formation of 30 the fabric. Backward motion of the take-up rollers is prevented by a pawl 117 pivoted to the shaft 10 and engaging the gear wheel 111 in a manner to permit forward motion thereof and prevent backward motion thereof. Thus it will be seen that after 35 each time the pawl 82 has been rendered inoperative, by the arm 90 engaging the latch arm 94, the pawl 82 may be rendered operative or returned into engagement with 40 the ratchet wheel 80 at a predetermined period controlled by a projection 106 of the chain 102 at a predetermined period of the 45 operation of the machine.

From the foregoing description it will be 50 seen that during the operation of the machine, the pawl 80 remains constantly in engagement with the ratchet wheel 81 while the pawl 82 is moved into and out of operative engagement with the ratchet wheel 80 55 at predetermined intervals under the control of the pins 92 and the projections 106 of the pattern chain 102.

By this construction I am enabled to 60 greatly vary the designs of the product of the machine by not only changing the relation of the blocks 74, 75, 78 and 79 to each other upon the drums, 69 and 70, but also by actuating the drum 69 only at certain predetermined intervals which changes the timing of the movement of the blocks 74 and 78 carried by the drum 69 with relation to the movement of the blocks 75 and 79 carried by the drum 70.

I claim:—

65 1. In a knitting machine, the combination

of the needles, their support, the cam cylinder, actuating means for the cam cylinder, means carried by the cam cylinder to actuate the needles to produce stitches; two independently rotatable members, means for 70 rotating said members independently of each other, a thread-feeding part carried by the cam cylinder, and means controlled by each of said members for rendering said thread feeding part operative and inoperative at 75 predetermined intervals.

2. In a knitting machine, the combination of the needles, their support, the cam cylinder, actuating means for the cam cylinder, means carried by the cam cylinder to actuate 80 the needles to produce stitches, two independently rotatable members, means for rotating said members independently of each other, a thread feeding part carried by the cam cylinder, means controlled by each of 85 said members for rendering said thread feeding part operative and inoperative at predetermined intervals, a needle operating part, and means controlled by each of said members for moving said needle operating 90 part into and out of operative position.

3. In a knitting machine, the combination of the needles, their support, the cam cylinder, actuating means for the cam cylinder, means carried by the cam cylinder to actuate 95 the needles to produce stitches, two independently rotatable members, means for rotating said members independently of each other, a thread changing mechanism, and means controlled by each of said members 100 for operating the thread changing mechanism.

4. In a knitting machine, the combination of the needles, their support, the cam cylinder, actuating means for the cam cylinder, 105 means carried by the cam cylinder to actuate the needles to produce stitches, two independently rotatable members, means for rotating said members independently of each other, a thread changing mechanism, means 110 controlled by each of said members for operating the thread changing mechanism, a needle operating part, and means controlled by each of said members for moving said 115 needle operating part into and out of operative position.

5. In a knitting machine, the combination of the needles, their support, the cam cylinder, actuating means for the cam cylinder, means carried by the cam cylinder to actuate 120 the needles to produce stitches, means co-acting with the knitting instruments to affect the character of the fabric, two independently rotatable members, means for rotating said members, independently of each 125 other, and pattern controlling means carried by each of said members for operating the third named means.

6. In a knitting machine, the combination of the needles, their support, the cam cylin- 130

- der, actuating means for the cam cylinder, means carried by the cam cylinder to actuate the needles to produce stitches, means co-acting with the knitting instruments to affect the character of the fabric, two independently rotatable members, means for rotating said members independently of each other, including a pawl and a ratchet wheel, means for disengaging the pawl from the ratchet wheel at predetermined intervals, and pattern controlling means carried by each of said members for operating the third named means.
7. In a knitting machine, the combination of the needles, their support, the cam cylinder, actuating means for the cam cylinder, means carried by the cam cylinder to actuate the needles to produce stitches, means co-acting with the knitting instruments to affect the character of the fabric, two independently rotatable members, means for rotating said members independently of each other, including a pawl and ratchet wheel, means for disengaging the pawl from the ratchet wheel, a pattern chain, means for supporting and actuating said chain, means operated by the pattern chain for returning the pawl into engagement with the ratchet wheel, and pattern controlling means carried by each of said members for operating the third named means.
8. In a knitting machine, the combination of the needles, their support, the cam cylinder, actuating means for the cam cylinder, means carried by the cam cylinder to actuate the needles to produce stitches, means co-acting with the knitting instruments to affect the character of the fabric, two independently rotatable members, means for rotating said members independently of each other, including a pawl and ratchet wheel, means for disengaging the pawl from the ratchet wheel, a pattern chain, means for supporting and actuating said chain, a pivoted arm for raising said pawl from engagement with said ratchet wheel, means for raising said arm to engage and raise said pawl from engagement with said ratchet wheel, a latch to hold said arm in the raised position, means operated by the pattern chain for operating said latch to release said arm, and pattern controlling means carried by each of said members for operating the third named means.
9. In a knitting machine, the combination of the needles, their support, the cam cylinder, actuating means for the cam cylinder, means carried by the cam cylinder to actuate the needles to produce stitches, means co-acting with the knitting instruments to affect the character of the fabric, a rotatable member, means for rotating said member, including a pawl and ratchet wheel, means for disengaging the pawl from the ratchet wheel, means for feeding the fabric from the needles, a fabric-operated wheel in the path of the fabric and rotated thereby, a pattern chain, means operated by the fabric-operated wheel for supporting and actuating said chain, means operated by the pattern chain for returning the pawl into engagement with the ratchet wheel, and pattern controlling means carried by said member for controlling the third named means.
10. In a knitting machine, the combination of the needles, their support, the cam cylinder, actuating means for the cam cylinder to actuate the needles to produce stitches, means co-acting with the knitting instruments to affect the character of the fabric, including a pawl and ratchet wheel, means for disengaging the pawl from the ratchet wheel, means for feeding the fabric from the needles, a fabric-operated wheel in the path of the fabric and rotated thereby, a pattern chain, means operated by the fabric-operated wheel for supporting and actuating said chain, means operated by the pattern chain for returning the pawl into engagement with the ratchet wheel, and pattern controlling means carried by each of said members for operating the third named means.
11. In a knitting machine, the combination of the needles, their support, the cam cylinder, actuating means for the cam cylinder to actuate the needles to produce stitches, means co-acting with the knitting instruments to affect the character of the fabric, two independently rotatable drums, pattern-controlling means carried by said drums to operate the third named means, means for rotating said drums independently of each other including a pawl and a ratchet wheel, a pivoted arm for raising said pawl from engagement with said ratchet wheel, and means carried by the ratchet wheel for engaging and raising said arm to engage and raise said pawl from engagement with the ratchet wheel.
12. In a knitting machine, the combination of the needles, their support, the cam cylinder, actuating means for the cam cylinder to actuate the needles to produce stitches, means co-acting with the knitting instruments to affect the character of the fabric, two independently rotatable drums, pattern controlling means carried by said drums for operating the third named means, means for rotating said drums independently of each other, including a pawl and a ratchet wheel, means actuated by the ratchet wheel for disengaging the pawl from the ratchet wheel, a pattern chain, means for supporting and actuating said chain, and means operated by the pattern chain for returning said pawl into engagement with the ratchet wheel.

13. In a knitting machine, the combination of the needles, their support, the cam cylinder, actuating means for the cam cylinder, means carried by the cam cylinder to 5 actuate the needles to produce stitches, thread-feeding parts carried by the cam cylinder, an operating cam for said parts, two independently rotatable members, means for rotating said members independently of 10 each other, and means controlled by each of said members for moving said cam into position to act upon the thread-feeding mechanism.
14. In a knitting machine, the combination of the needles, their support, the cam cylinder, actuating means for the cam cylinder, means carried by the cam cylinder to 15 actuate the needles to produce stitches, thread-feeding parts carried by the cam cylinder, an operating cam for said parts, two independently rotatable drums, means for 20 rotating said drums independently of each other, adjustable patterning parts carried by each of said drums, means controlled by the patterning parts of 25 each of said drums for moving said cam into position to act upon the thread-feeding mechanism.
15. In a knitting machine, the combination of the needles, their support, the cam cylinder, actuating means for the cam cylinder, means carried by the cam cylinder to 30 actuate the needles to produce stitches, thread feeding parts carried by the cam cyl-
- inder, an operating cam for said parts, a 35 rotatable drum, means for rotating the drum, adjustable patterning parts carried by the drum, means controlled by patterning parts of the drum for moving said cam into position to act upon the thread feeding mechanism, a pattern-controlling, needle-operating cam, and means controlled by other patterning parts of the drum for operating the needle operating cam.
16. In a knitting machine, the combination of the needles, their support, the cam cylinder, actuating means for the cam cylinder, means carried by the cam cylinder to 40 actuate the needles to produce stitches, thread-feeding parts carried by the cam cylinder, an operating cam for said parts, two independently rotatable drums, means for 45 rotating said drums independently of each other, adjustable patterning parts carried by each of said drums, means controlled by patterning parts of each of said drums for moving said cam into position to act upon the thread-feeding mechanism, a pattern-controlling, needle-operating cam, and means controlled by other patterning parts of each 50 of said drums for operating the needle-operating cam.

In testimony whereof I affix my signature in presence of two witnesses.

EDGAR C. CHANDLER.
